UNITED STATES PATENT OFFICE.

DAVID SHIELDS, OF EDGEWORTH, PENNSYLVANIA.

MANUFACTURE OF FERTILIZERS.

1,212,573.

Specification of Letters Patent. Patented Jan. 16, 1917.

No Drawing.

Application filed November 23, 1916. Serial No. 132,998.

To all whom it may concern:

Be it known that I, DAVID SHIELDS, residing at Edgeworth, in the county of Allegheny and State of Pennsylvania, a citizen 5 of the United States, have invented or discovered certain new and useful Improvements in the Manufacture of Fertilizers, of which improvements the following is a specification.

10 My invention relates to improvements in the manufacture of fertilizers. Letters Patent of the United States, No. 913,922 (March 2, 1909,) and No. 1,196,889, (September 5, 1916,) have heretofore been 15 granted me in this field.

My present invention consists in improvements in the method of manufacture which is described in the later of the two patents named, No. 1,196,889, and particularly concerns 20 the matter of the temperature to which the mixture of coal and subterranean salt water is subjected, whereby I am enabled to dispense with the step of aging as described in the patent. These and other 25 matters indicating adaptations of my invention will appear in the ensuing description.

As in my earlier invention, I take coal or other carbonaceous material, and, if not already in finely divided condition, I bring it 30 to such condition. My preferred material is bituminous coal, and I grind it, if necessary, to particles which will pass through a sieve with meshes 8 to 30 to the inch. Anthracite coal should be ground somewhat 35 finer; softer carbonaceous substances, such as peat and lignite, need not be ground so fine. In the usual commercial operations at anthracite mines, the mined coal is washed and a great deal of coal in finely divided 40 state is washed away; some of this is reclaimed; but some of it, formerly carried away in streams and rivers, is now, because of the requirements of state laws, deposited as silt. This silt deposit of anthracite coal 45 has no present commercial value. I find it well adapted to my purpose. I mix, as before, with the finely divided carbonaceous material a solution of mineral salts, which preferably is, or at least is essentially like. 50 the well-known subterranean waters which flow from oil and gas wells. I have found that such subterranean water, when used in the operation here described, while serving the desired end, does not leave in the resulting fertilizer any harmful substances. The density of this natural water varies con-

siderably, and in any case considerable latitude in proportions is permissible; ordinarily five ounces by weight of this subterranean water will on evaporation leave two 60 ounces of salts. I have found that good results are obtained by combining with every thirty pounds of ground coal six pounds of the dry salt, or fifteen pounds by weight of the native subterranean water of the degree 65 of concentration indicated.

The mixed mass is heated for a sufficient time to cause the salts to impregnate the coal, leaving the particles of coal in softened condition. This is advantageously accomplished by placing the mixture of coal and salt water in a closed vessel and subjecting it to a hot water bath. In my earlier Patent No. 1,196,889, I recommended a temperature not exceeding 130° F. continued for 18 75 to 20 hours. I have since discovered that by raising the temperature to the boiling-point of water or to approximation thereto, the period of heating may be diminished, and need not be continued only from about 80 8 to 12 hours, and furthermore, after such treatment at higher temperature the ultimate step of the operation as previously described, that is the step of aging, becomes unnecessary. I find that in this matter of 85 temperature the best results are attained by maintaining the water bath at a slow boil.

After the mixture has been heated as above described, I mix with the impregnated coal powdered clay or a similar substance. The 90 clay which I prefer to use is a fine clay commonly found in and often immediately beneath deposits of bituminous coal, but other clay may be used with success. The carbonaceous slate commonly found in coal 95 mines associated with the coal, and constituting with clay the mine refuse called by the miners "gob," I have found to be an excellent material for use here. The slate is of course reduced to finely divided condition, 100 to the condition of clay, in fact, and is then mixed with the impregnated coal. It is preferred to mix the impregnated coal and clay (or slate) together in proportions of about two to one by weight of the coal component 105 to the clay (or slate) component; nevertheless a less percentage of the impregnated coal may be mixed with the clay (or slate) and desirable fertilizing qualities obtained. I have here indicated that the slate (particularly the carbonaceous slate such as is found in coal mines) which may be ground and used 110

as clay is used to mix with the coal to accomplish my invention. In the ensuing claims I mean to include in the term "clay" not only material found disintegrated in native state, but also clay such as I produce by grinding the slate which I have here mentioned.

The material so prepared is ready for service, and does not require the aging which 10 is a feature of the method described in my earlier Patent No. 1,196,889.

A further feature of my present invention is this, that instead of mixing the clay (or slate) with the coal after the latter substance has been treated with saline water, 15 the clay (or slate) and the coal may be mixed first, and the saline water may be added to the mixture, and the whole may then be heated, in like manner as the coal 20 has already been described to be heated.

I claim as my invention:

1. The method of manufacturing fertilizer which consists in mixing carbonaceous material in finely divided condition with subterranean salt water, subjecting the mixture 25 to a temperature approximating the boiling-point of water, and adding to the so-treated material clay in finely divided condition.

2. The method of manufacturing fertilizer which consists in subjecting the carbon component of a mixture of finely divided coal and finely divided clay to the action of subterranean salt water while at a temperature of 212° F. 30

In testimony whereof I have hereunto set 35 my hand.

DAVID SHIELDS.

Witnesses:

FRANCIS J. TOMASSON,
ROBERT H. KOHL.

Corrections in Letters Patent No. 1,212,573.

It is hereby certified that in Letters Patent No. 1,212,573, granted January 16 1917, upon the application of David Shields, of Edgeworth, Pennsylvania, for an improvement in the "Manufacture of Fertilizers," errors appear in the printed specification requiring correction as follows: Page 1, line 80, strike out the word "not"; same page, line 112, strike out the word "which"; and that the said Letters Patent should be read with these corrections therein that the same may conform to the record of the case in the Patent Office.

Signed and sealed this 6th day of February, A. D., 1917.

[SEAL.]

R. F. WHITEHEAD,
Acting Commissioner of Patents.

Cl. 71—9.
